GUY DERRICK

Raymond O. Lively, St. Louis, Mo.

Application August 9, 1944, Serial No. 548,755

6 Claims. (Cl. 212—57)

1

This invention relates to new and useful improvements in derricks, and more particularly to a guy derrick such as is employed on high building construction and moved from one floor level upwardly to the next as work progresses.

At present, considerable time and manual efforts are consumed in raising a conventional derrick from one floor level upwardly to the next. There is much dismantling and hoisting of parts and the ever present danger of personal injury to workmen.

The principal object of the present invention is to reduce the engineering requirements in jumping a derrick from one floor level to another.

Another important object of the invention is to provide a derrick having an extensible mast section which can be elevated to an overlying floor level on a building construction and secured in place at the new level, after which the remaining part of the mast and the boom are elevated by means complementary to the elevated section, until the entire assembly is jumped to the new level where it can be adequately secured in place.

Various other important objects and advantages of the invention shall become apparent to the reader of the following description.

In the drawings:

Figure 1 is a fragmentary side elevational view with a portion in section showing the improved derrick before it is jumped upwardly to the next floor level.

Figure 2 is a fragmentary side elevational view, partly in section, showing the outer section of the mast after it has been elevated to the new floor level and preparatory to lifting the inner mast section along with the boom.

Figure 3 is a vertical sectional view through the derrick.

Figure 4 is a sectional view taken substantially on line 4—4 of Figure 3.

Figure 5 is a cross sectional view taken substantially on line 5—5 of Figure 3.

Figure 6 is a top plan view of the cribbing erected on the upper floor level of the building structure to support the outer mast section in place for the raising of the inner mast section, the telescoped mast sections being shown in cross section.

Figure 7 is a side elevation of the structural assembly of Figure 6.

Referring to the drawings wherein like numerals designate like parts, it can be seen that numeral 5 denotes the upright steel beams of a

2

building construction, while reference numerals 6, 7 represent the horizontal beams of two floor levels.

The derrick proper is generally referred to by numeral 8, and as shown in Figure 1, is resting at the floor level 6. Cribbing or supporting beams 9 are suitably disposed on the construction beams 6 and these serve to support plates 10, 10, the opposed ends of which are shaped to form hemispherical-shaped shells 11, flanged, as at 12, and bolted together, as at 13. These shells together define a socket for the reception of a hollow ball 14, open at its bottom to match an opening in the bottoms of the sockets 11, 11. The ball 14 is connected by a neck 15 to a base 16 from which rises a mast generally referred to by numeral 17. Pivotal secured to the base 16, as at 18, is a boom generally referred to by numeral 19.

20 The boom 19 may be constructed of welded elongated plates 20 for its full length, or may be interrupted or entirely constructed of steel beams 21 provided with spreaders 22 and brace means 23. In order to lighten the upper portion 25 of the boom, it may be desirable to have this open construction at the upper end only, as best shown in Figure 1.

At the upper end of the boom 19 is a clevis 24 supporting a sheave 25.

30 A cable 26 extends downwardly to a sheave 27 carrying a material-handling hook or the like 28, and then upwardly over the sheave 25 and a small pulley wheel 29 supported by the upper end of the boom 19. From there the cable 26 35 extends downwardly about a pulley 30 mounted on a bracket 31 at the lower end of the mast 17. The cable 26 then extends through an opening 32 in the wall of the mast, passes over a pulley wheel 33 mounted within the lower portion of 40 the mast and then downwardly through the ball and socket support 14, 11, the base 16 having a passageway for all cables extending below the derrick.

The mast 17 consists of two main parts, namely, 45 an inner section 34 and an outer section 35. The inner section 34 tapers downwardly at its lower portion and is adequately secured to the base 16. Just above the base 16, the lower tapered portion of the inner section 34 has an angle member or shelf 36 secured thereto and serving as a top for the lower end of the outer section 35.

The upper portion of the inner section 34 is tapered and the upper portion of the outer section 35 is likewise tapered.

As can be seen in Figure 3, a pin 37 rises from

the upper end of the mast section 35 and supports a disc 38 apertured at its peripheral portion to receive the upper ends of guy lines 39 which extend outwardly to engage pulleys 40 on portions of the building construction and then downwardly to crabs or anchoring means at convenient places on the building construction, this being so that when it is desired to elevate the derrick structure, these guy lines can be released at the point where the lifting power for control mast is located.

A bracket 41 is provided on the upper portion of the outer mast section 35 and supports a sheave 42. A cable 43 extends from this point out to the upper end of the boom 19, over a sheave 44 carried by the upper end of the boom, and which in turn is supported by a clevis 45, and then backwardly and over the sheave 42, from where it extends downwardly and under the sheave 30 and over the pulley 33 after passing through the opening 32 in the lower portion of the mast section 34. This cable 43 also extends downwardly through the base 16 and ball and socket support 14, 11.

A bracket 46 depends within the upper portion of the outer mast section 35, supporting a sheave 47. A cable 48 anchored to the upper end of the inner mast section 34 extends upwardly and over the sheave 47 and then downwardly between the mast sections 34, 35 to pass against a pulley 49 and the pulley 33, from where it extends downwardly through the base 16 and ball and socket support 14, 11.

Although not shown, it is apparent that the cables 26, 43 and 48 extend downwardly below the derrick to a suitable operating point where power-operated winches or other means are employed.

Extending from this unshown operating point and upwardly through the ball and socket support 14, 11 and the base 16 is a cable 50 which extends upwardly through the inner mast section 34 to pass over a sheave 51 in the upper end of the inner mast section. The cable 50 passes outwardly through an opening in the mast section at this point and then downwardly between the mast sections to connect to an anchor 52 on the inside of the lower portion of the outer mast section 35.

At this point, it would be well to consider the specific construction of the inner and outer mast sections. While it is entirely feasible to construct the sections out of steel beams, spreaders and various bracing elements, it has been found practicable for the purpose of the present invention to construct the mast sections of sheet metal, welding these sections together and in a form clearly shown in the drawings. In welding the sheets of metal of the inner mast section or otherwise constructing this inner section, it is preferable that longitudinally extending enlargements 53, 53 be provided at a pair of the corners and flanges 54, 54 at the remaining corners, these enlargements and flanges being outstanding in such a manner that the side walls of the inner section do not contact the side walls of the outer section. Due to the width of the flanges 54, 54, a substantially wide passageway 55 results between the opposed side portions of the inner and outer sections to serve as a passageway for the cables 48, 50.

A loop 56 is provided on the lower portion of the inner mast section 34 to be used with a pull stick (not shown).

At the lower end of the outer mast 35 is a pair

of oppositely disposed loops 57, 57, to receive supporting timbers 59, for purposes presently to be explained.

In the operation of the derrick, it can be seen that the cable 43 is employed for moving the boom upwardly or allowing the same to lower. The cable 26 takes care of the lifting and lowering of a load regardless of the position of the boom 19. As before stated, both of these cables extend downwardly below the derrick and are controlled by power winches or the like (not shown).

The cable 50 extends upwardly and through the upper portion of the inner mast section 34 and downwardly to the lower portion of the outer mast section and when operated serves to elevate the outer mast section to the next floor level, as shown in Figure 2. The remaining cable 48 extends upwardly from a power winch or the like (not shown) through the base 16 and upwardly through the channelway 55 between the mast sections to pass over the pulley 47 and attach to the upper end of the inner section 34, and when operated serves to elevate the inner section 34 along with the boom 19 to the new position which has been established by the outer mast section 35.

More specifically stated, the outer mast section 35 is elevated from the position shown in Figure 1 when it is desired to jump the derrick from one level upwardly to another. When the outer mast section 35 has been elevated above the new floor level, a crib will be built and the timbers 59 inserted through the loops 57 to support said mast section in place thereon. This lifting of the outer section takes place as the guy lines 39 are released and upon establishment of the outer mast section in its new location, the guy lines are fixed and the inner mast section along with the boom 19 are lifted to the new location by power exerted on the cable 48. Obviously, when the inner mast section and the boom have been elevated to the new location, the plates 10, 10 can be secured in the same manner as they were secured in place on the construction girders 6 of the underlying floor level.

As shown in Figures 6 and 7, the aforesaid crib is made up of crossed timbers 58, 58a, laid on parallel structural elements 7 of the upper floor level. When in place, the outer mast section 35 is supported on the uppermost cribbing timbers 58a, by the timbers 59 engaged through the loops 57, substantially as shown. In elevating the inner mast section 34, the supporting timbers 9 are first detached from the plates 10 and thereafter are placed in position on the structural elements 7 for the securing of the plates 10 thereto, as in the first instance, as soon as the base structure of the derrick is elevated to clear the structural elements 7.

While the foregoing specification sets forth the invention in specific terms, it is to be understood that numerous changes in the shape, size and materials may be resorted to without departing from the spirit and scope of the invention as claimed.

Having described the invention, what is claimed as new is:

1. The method of elevating a derrick having a two-part extensible mast from one floor level to another on a building construction, said mast including a boom, which consists in elevating one portion of the extensible mast above a next adjacent floor level, anchoring the elevated portion of the mast, then elevating the remaining portion

of the mast and the boom by aid of the anchored elevated portion to the new position, and thereafter securing the last-mentioned portion of the mast and boom in the new position.

2. A derrick of the character described comprising a base, means for temporarily supporting the base on one floor level of a building construction, a mast rising from the base, said mast consisting of a pair of sections, one secured to the base and the other extensible on the first-mentioned section, a boom swingably supported on the base, a cable for elevating and lowering the extensible section, means for temporarily supporting the extensible section in the next adjacent floor level, a second cable for operating the boom, a material handling element mounted on the free end of the boom, and a third cable for operating the element, said base having an opening therein through which the cables depend to an operating point.

3. A derrick of the character described comprising a base, means for removably securing the base on one floor level of a building construction, a mast raising from the base, said mast consisting of a pair of sections, one secured to the base and the other extensible on the first-mentioned section, a boom swingably supporting on the base, means for elevating and lowering the extensible section, means extending from the upper end of the extensible section for actuating the boom, and means for the temporary securement of the extensible section to an overlying floor structure to allow for movement of the first mentioned section relatively thereto.

4. A derrick of the character described comprising a base, means for temporarily securing the base on one floor level of a building construction, a mast rising from the base, said mast consisting of a pair of sections, one secured to the base and the other extensible on the first-mentioned section, a boom swingably supported on the base, means for elevating and lowering the extensible section, means for its temporary securement to an over-lying floor level structure, and a hoist line trained over a pulley on the extensible section and connected to the first-mentioned section for elevating the same and said boom to elevated anchored position of the extensible section.

5. A derrick of the character described comprising a base, means for removably securing the

base on one floor level of a building construction, a mast rising from the base, said mast consisting of a pair of sections, one secured to the base and the other extensible on the first-mentioned section, a boom swingably supported on the base, cables for controlling the extensible section and said boom, a ball carried at the lower side of a supporting plate below said base and removably secured to parallel timbers adapted to span floor level structural elements, and a socket formed centrally in said plate to receive said ball, said ball and the socket having a lined opening for the passage of said cables downwardly therethrough for manipulation.

15 6. A derrick of the character described comprising a mast constructed of a pair of telescopic sections, a base on which one of the sections is mounted, means for removably securing the base on one floor level of a building construction, a boom swingable on the base, control cables for lifting the upper-mast section on the lower-mast section, a second means for pulling the lower-mast section to a position established by the upper-extended mast section, means for temporarily supporting the upper-mast section on the next adjacent floor level, means extending from the top of the upper-mast section for actuating the boom, said telescopic sections being spaced apart to define a passageway for said cables to depend therethrough for manipulation from a point below the derrick, and means on the lower-side of said base for securing the derrick to timbers adapted to span floor-level structural elements.
